UNITED STATES PATENT OFFICE.

JOHN GEDNETZ, OF BELOIT, OHIO.

DESIGN FOR A STATUE.

No. 38,818.

Specification for Design.

Patented Sept. 17, 1907.

Application filed August 17, 1907. Serial No. 389,075. Term of patent 3½ years.

To all whom it may concern.

Be it known that I, JOHN GEDNETZ, a citizen of the United States, residing in Beloit, in the county of Mahoning and State of Ohio, have invented a new, original, and ornamental Design for a Statue, for which the following is a specification, reference being had to the accompanying drawing, forming part thereof.

The figure is a plan view of a statue showing my design.

I claim:

The ornamental design for statue as shown.

JOHN GEDNETZ.

Witnesses:

J. S. MILLER,
GEO. R. DIVER.
